United States Patent Office

Des. 179,350
Patented Dec. 4, 1956

179,350

SHOE OR SIMILAR ARTICLE

Faie Joyce, Pasadena, Calif., assignor to Joyce, Inc.,
Pasadena, Calif., a corporation of California

Application May 5, 1955, Serial No. 35,829

Term of patent 3½ years

(Cl. D7—7)

The dominant features of my design are shown in full lines.

I claim:

The ornamental design for a shoe or similar article, as shown and described.
